UNITED STATES PATENT OFFICE.

AUGUSTUS J. HARPSTRITE, OF LOS ANGELES, CALIFORNIA, ASSIGNOR OF ONE-HALF
TO FREDERICK A. HARPSTRITE, OF LOS ANGELES, CALIFORNIA.

COMBINATION AIR, LAND, AND WATER PLANE.

Application filed November 12, 1924. Serial No. 749,495.

To all whom it may concern:

Be it known that I, AUGUSTUS J. HARPSTRITE, citizen of the United States, and resident of Los Angeles, State of California, have invented new and useful Improvements in Combination Air, Land, and Water Planes, of which the following is a specification.

This invention relates to vehicles and 10 more particularly to a flying vessel of the heavier-than-air type.

An object of the invention is to provide a craft adapted for flying, for land travel, and for water travel. An object is to provide 15 an aerial vessel having a main supporting plane which is adjustably mounted on an axis transverse to a cabined hull and which plane lies longitudinally of the hull and head on above the bow of the boat. An object is to provide a positive means and an 20 auxiliary safety means for controlling the angle of tilt of the plane for ascending and descending.

An object is to provide an air craft having 25 four main ground wheels for permitting the craft to be propelled by its air propeller while aground, and an object is to provide means for castering the front wheels to steer the vessel for land running.

An object is to shroud the front wheels 30 to reduce air resistance when flying.

An object is to provide a hull having a plane-forming bottom and which also provides, along each side, a separate fuel tank 35 below an inner bottom.

An object is to provide safety brakes for the various controls. And an object is to generally provide for a reduction of air resistance by construction and arrangement of 40 the parts to the end that a very high speed may be obtained in air travelling.

An object is to provide the vessel with a direct-lift action propeller to aid the plane element in making ascent and descent, and 45 to provide control means for throwing this propeller into and out of effect.

The invention consists of apparatus more particularly described in the following specification referring to the accompanying 50 drawings, wherein,

Figure 1 is a perspective of the craft. Figure 2 is a cross-section of the prow, showing the slide operating pinion. Figure 3 is a plan of the steering wheel operating

device arranged in the boat bow. Figure 55 4 is a central, longitudinal section of the craft. Figure 5 is a front elevation of the adjusting slide. Figure 6 is a plan of elements of the controls. Figure 7 is an elevation of control brake. Figure 8 is a vertical cross-section on a plane just in front of the axle of the top, main plane. Figure 9 is a diagram of the rudder working bight. Figure 10 shows the craft equipped with a direct-lift action propeller. Figure 11 is a perspective showing scoop planes to throw air from the head propeller up into the parachute or top plane. Figures 12 and 13 show in detail the air propeller.

The craft comprises a boat body having 70 upwardly convergent side walls 2 joining a sloping top deck 3 having lateral side wings 4 along the corners. These wings are braced at 5 and have tension lines 6 connected to a crossbeam 7 at the bow of the 75 body. The bow has a fore deck 8 inclining up to a central cabin transom 9, windowed fore, aft and laterally giving clear view for the aviator from a seat 10 in the cabin.

A feature of the invention consists of 80 forming the outer bottom of the hull with outwardly and downwardly divergent plane faces 11 to give lifting action on air or on water.

An inner cabin floor 12, from side to side, 85 forms separate tanks 13 for carrying separate supplies of liquid fuel, so that should one tank spring a leak, the other has a safety reserve.

On the boat keel 14 is secured a suitable 90 motor M having a rear clutch 15 to connect with and drive a shaft 16 having a propeller 17 to drive the craft while afloat.

Water tight doors 18 provide for easy entrance and exit while at rest on land, and a 95 deck hatch 19 provides for ingress and egress while afloat.

At the front end of the motor is a clutch and drive mechanism 20 for connecting up a shaft 21 mounted in and extending from the 100 bow and carrying an air propeller 22. The propeller has blades medially secured to the rear edge of a re-enforcing cylinder 23 having a front knife edge to reduce air resistance. This enables use of a propeller of 105 large sweep and high pitch for high speed without danger of snapping off the blades.

To obtain speed in air flight and also in-

crease safety I provide an elongated, tunnel-shaped top, main flying plane 25 of approved structural embodiment, preferably of smooth inside and outside surface, as of 5 aluminum sheets, to reduce air resistance. The plane has a salient, curved nose 26 and is amply provided with transverse beams 27 and skeleton carlines 28 and stringers 29. This plane is disposed longitudinally 10 along and above the boat body and, by virtue of its size, and its arched form, provides a material parachute effect in descending. The plane 25 is mounted, rearwardly of its longitudinal center, on an axle 30 journaled 15 in posts 31 extending up from the boat.

Positive means are provided for tilting the top plane 25 to vary the angle of incidence. Also, an auxiliary or safety control means is provided for use if the former 20 means give way.

The positive means includes a slide 33 slotted at 33^a to pass over the propeller shaft 21 and being slidably mounted in bow standard 34 which is curved concentric to the axis 25 of the axle 30 as, also, is the slide 33. The latter is securely attached to a crossbeam 35 of the top plane and has a rack 36 engaged by a pinion 37 fixed on the front end of a flexible shaft 38 extending back into the 30 cabin. The shaft has a worm gear 39 engaging a worm 40 on a sleeve 41 turning on a stout cross-bar 42. The sleeve is turned by a hand wheel 43. While the worm and gear may hold the shaft 38, I prefer to employ a brake operative to prevent slipping of the slide 33 after it has been set by the aviator operating the wheel 43. Such a brake is shown in Figure 7 as including a drum 50 on which is a turn of cable 51 fast 40 at one end and attached to a spring 52 at the other, which tightens the cable bight to hold the drum. Pressure on a pedal 53 slacks up the cable so that the drum and its shaft can turn.

45 Strong braces 55 connect the slide 33 to the sides of the top plane 25. This is also well trussed up by guy lines 56.

The auxiliary control means includes a pair of reins 57 having lines 58 running 50 back to a reel 58^a on rod 41. This reel may attach to wheel 43 and so pull back or let out the reins which connect the boat bow and the fore end of the top plane. The reel, if independent, may have its own brake device 55 50^a (similar to brake 50).

60 Direction of flight is controlled by a tail rudder 60 pivoted on a vertical hinge 61 and having a rope bight 62 led to remote pulleys 63, at opposite sides of the plane and thence to rear pulleys 64, thence down to a drum 65 loose on the cross-rod 41. This drum is turned by a hand wheel 66 and held fast by a manually released brake 50^b.

65 In addition to providing for air and water travel by the craft, I also provide for land

travel and turning movements, utilizing the air propeller 22 for propulsion. To that end I mount rear ground wheels 68 and front steering wheels 69, which have knuckle arms 70 connected by a drag link 71 arranged in a cross-tube 72 in the hull so that water may freely enter. Into this tube extends a packed steering post 73 having a spool 74 with a few turns of cable 75 leading out and attached to the steering link 71. At one point the cable is attached to the spool so as to prevent slip. The post has at the inner end a removable steering wheel 76 for operation by the aviator while running on land.

A lever 78 controls clutches 15—20 to throw out propeller 17 when propeller 22 is driven and vice versa.

Safety lines 80 connect the ends of the main plane and the ends of the boat body to insure a parachute action in any emergency.

To reduce head resistance sharp nose shrouds 81 nearly enclose the front running wheels 69.

A central landing wheel 82 is mounted at the bottom end of the prow.

As shown in Figure 10, another feature of the craft consists of a top propeller 84 having a vertical shaft 85 sliding up and down in a fixed, central tubular bearing 86 projecting nearly to the top of the arched main plane and being guyed by wires 87 to the boat. The lower end of the shaft 85 is splined in a hollow shaft 88 having a gear 89 meshing with another gear 90 on a sleeve 91 having a clutch 92 for connecting it to the motor shaft.

Thus the top or lifting propeller can be driven at will with or without the propellers 17—22 or either of them.

I prefer to make the top propeller 84 of disappearing form and therefore form a depression 25^a in the crown of the plane 25 which may be concave or up curved longitudinally as well as transversely, (Fig. 10). A slot 94 in the depression bottom allows the plane to tilt clear of the upright 86.

On the shaft 85 is a collar 95 having pins 96 connected to endless cables 97 fixed to a spool 98 aside of the shaft. This spool is turned by a gear means and crank 99 thereby raising the propeller 84 out of the recess 25^a to a desired degree, or lowering it.

The combined effort of main plane 25 and propeller 84 is, therefore, to cause a quick take-off when propeller 22 is speeded up. The propeller 84 may be used to retard descent in conjunction with the parachute-plane 25.

As shown in Figure 11, air-diverting planes 100 may be provided at the bow of the boat body to throw air from the propeller 22 up into the top plane. The planes 100 may be released at the bottom from the boat and then hinged out on rods 101 so that for water reserve, they will not check speed.

Power means of any kind may be used to operate the plane adjusting mechanism, especially in the larger size crafts.

It is understood that the propeller 22 may be set with its ring either in front or in rear of the blades.

When the craft is afloat the top propeller 84 can be run fast enough to keep the boat steady when there happens to be a heavy sea running.

Ample side wings 103 give lateral stability to the craft when flying, and the top propeller 84 will be highly assistful in steadyng boat when the air is in a pockety condition, or tends to roll the craft.

What is claimed is:

1. A combined land, air and water vessel including a boat body having front steering wheels, rear running wheels, means in the body for operating the steering wheels for land travel, fixed side planes along the body, a main flying plane of concaved under face lying longitudinally over and along the boat, means for tilting the plane longitudinally to vary the angle of incidence, and a rudder for aerial flying.

2. A combined land, air and water vessel including a boat body provided with a driven propeller, a longitudinally, extending, top plane pivoted transversely of the boat, an aerial rudder, a bow rack connected to the plane and sliding on the boat prow and guided in a path having the plane pivot as its axis, and a control means including a pinion engaging the rack to raise and lower the bow end of the plane.

3. A combined land, air and water vessel including a boat body provided with a driven propeller, a longitudinally, extending, tunnel-shaped top plane pivoted transversely of the boat, an aerial rudder, a bow rack connected to the plane and sliding on the boat prow, and a control means including a pinion engaging the rack to raise and lower the bow end of the plane and a second and safety, auxiliary plane-control means.

4. A land, air and water vessel including a boat body with rear running and front steering wheels for land use, a longitudinally extending, main flying plane, arched transversely and having a transverse axle in the boat body, and a bridle means for controlling the angle of the plane as to the boat.

5. A land, air and water vessel including a boat body with rear running and front steering wheels for land use, a longitudinally extending, main flying plane, arched transversely and having a transverse axle in the boat body, and a bridle means for controlling the angle of the plane as to the boat and an air rudder lying below and tilting with the plane.

6. A land, air and water vessel including a boat body with rear running and front steering wheels for land use, a longitudinally

extending, main flying plane, arched transversely and having a transverse axle in the boat body, and a bridle means for controlling the angle of the plane as to the boat and an air rudder lying below and tilting with the plane and a steering rope leading from opposite sides of the rudder tail to and down from the axle to the control pit in the boat.

7. An aerial vessel including a boat body having a longitudinally extending, main supporting plane mounted on an axle transverse the boat body, a prow structure extending upward from the body and being curved concentric to the center of the said axle, a slide fitting and moving up and down in the prow and being attached to the front end of the said plane, and control means for operating the slide to determine the angle of the plane.

8. An aerial vessel including a boat body having a longitudinally extending, main supporting plane mounted on an axis transverse the boat body, a prow structure extending upward from the body and curved concentric to the said axis, a slide adjustably mounted in the prow and including a rack, and a pinion engaging the rack and having control means in the boat body, the slide being connected to the front end of the plane to tip it on the axis.

9. An aerial vessel including a boat body having a longitudinally extending, main supporting plane, a transverse axle on the body and carrying the plane, a prow structure extending upward from the boat body and concentric to the axle, a propeller in front of the prow and having its shaft extending back through the prow into the body, a slotted slide movable up and down in the prow, said shaft passing through the slot in the slide, and control means in the body of the boat for adjusting the plane by said slide.

10. An aerial vessel including a boat body having a longitudinally extending, main supporting plane pivoted on an axis transverse the boat body, a slide mounted centrally and adjustably in the prow of the boat and connected by a cross arm to the front end of the plane, rack and pinion means for adjusting the slide, and means extended to the cock-pit of the boat for controlling said slide.

11. An aerial vessel including a boat body having a longitudinally extending, main supporting plane pivoted on an axis transverse the body, a slide adjustably mounted in the prow of the body, means connecting the slide to the front end of the plane, manual control means to shift the slide to vary the angle of the plane above the boat, a power plant in the boat, a propeller shaft passing through the slide and having a propeller in front of the prow and being driven

by the said plant, and a water propeller at the stern driven by the power plant.

12. An aerial vessel including a boat body, a main lifting plane longitudinally disposed above the body and having a transverse axis on the body, a tail rudder mounted in the plane, a head propeller for the vessel, a slide at the prow of the vessel for tilting the plane on its axis, a transverse fixed rod in the boat body, and independently operative means on the said rod for controlling the rudder and the said slide.

13. An aerial vessel including a boat body, a main lifting plane lying parallel to and above the body and tilting on a transverse axis thereon, positive mechanism for tilting the front end of the plane up or down, and a safety means for controlling the plane in event of failure of the said mechanism, and including flexible connections between the boat and the front end of the plane, and a hauling-in means attached to the connections to vary the angle of the plane.

14. An air craft having, in combination, a boat with a power plant, a main flying plane, a bow tractor propeller, a shiftable lifting propeller above the plane, and means for selectively, or concurrently, driving the propeller from the power plant.

15. An air craft having, in combination, a boat with a power plant, a main flying plane, a bow propeller, a lifting propeller above the plane, and means for selectively, or concurrently, driving the propellers from the power plant, and means for raising and lowering the lifting propeller.

16. An air craft having, in combination, a boat with a power plant, a main flying plane, a bow propeller, a lifting propeller above the plane, and means for selectively, or concurrently, driving the propellers from the power plant, and means for raising and lowering the lifting propeller; the plane having a recess in its top for receiving the lowered top propeller.

AUGUSTUS J. HARPSTRITE.
